US00D997567S

(12) **United States Design Patent** (10) Patent No.: **US D997,567 S**
(45) Date of Patent: ** Sep. 5, 2023

(54) **ELECTRIC TOOTHBRUSH**

- (71) Applicant: **Colgate-Palmolive Company**, New York, NY (US)
- (72) Inventors: **Takahide Okai**, Highland Park, NJ (US); **Brian Bloch**, Hillsborough, NJ (US); **Brett Newman**, San Francisco, CA (US); **Kyle Swen**, San Carlos, CA (US); **Francois Dransart**, San Francisco, CA (US); **Carly Byungyeon Kim**, San Francisco, CA (US)
- (73) Assignee: **Colgate-Palmolive Company**, New York, NY (US)

(**) Term: **15 Years**(21) Appl. No.: **29/788,355**(22) Filed: **May 7, 2021****Related U.S. Application Data**

- (62) Division of application No. 29/652,907, filed on Jan. 6, 2021, now Pat. No. Des. 922,074, which is a division of application No. 29/740,535, filed on Jul. 6, 2020, now Pat. No. Des. 911,713, which is a division of application No. 29/673,740, filed on Dec. 18, 2018, now Pat. No. Des. 891,784.
- (51) **LOC (14) Cl.** **28-03**

Primary Examiner — Karen E Eldridge Powers

CLAIM

The ornamental design for an electric toothbrush, as shown and described.

DESCRIPTION

FIG. 1 is a front perspective view of an electric toothbrush showing our new design;
FIG. 2 is a rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.
